UNITED STATES PATENT OFFICE.

GEORGE W. KORN, OF NEW YORK, N. Y.

BUTTON-HOLE CUTTER.

SPECIFICATION forming part of Letters Patent No. 247,766, dated October 4, 1881.

Application filed March 14, 1881. (No model.)

To all whom it may concern:

Be it known that I, GEORGE W. KORN, of the city of New York, in the State of New York, have made certain new and useful Improvements in Button-Hole Scissors, of which the following is the specification, reference being had to the accompanying drawings, and to the figures and letters of reference thereon.

The nature and object of my invention are to construct a pair of button-hole scissors, with the seat, fixing the definite play of the arms of the scissors, together with the screw-shaft, on which the nut forming the seat is located, between the arms, and also fixing a definite rest for each end of the shaft, in the manner and form as hereinafter shown.

Figure 1 shows a plan view. Fig. 2 is a sectional view through the line x x of Fig. 1.

Similar letters of reference refer to similar parts in the two figures.

A and B are the two arms of the scissors. In the arm A a screw-threaded shaft, D, is fixedly attached. Immediately opposite and in the arm B is a funnel-shaped hole, E, within 25 which fits the opposite end of the shaft D.

C is a nut, working on the screw-shaft D. The nut C is adjusted on the shaft D at pleasure,

to fix and limit the cut of the blades of the scissors, and the hole in the arm immediately opposite the screw-threaded shaft, within which 30 the end of the shaft fits, gives a support to the end of the shaft. Thus both ends of the shaft are supported, and the entire length of the shaft is confined within the outer edges of the arms. Consequently no end of the shaft extends 35 beyond the arms, and no opportunity is presented for them to catch on anything that might be in the way, as is the case in button-hole scissors now in use.

The shaft D can be located at any convenient 40 point on the arms of the scissors.

What I claim is—

As an article of manufacture, a button-hole cutter having the screw-shaft D securely fastened to one arm of the cutter at one end, and 45 the other end resting in a conical recess in the other arm of the cutter, the nut C working on the shaft D between the two arms, all constructed and arranged substantially as and for the purpose described.

GEORGE W. KORN.
